UNITED STATES PATENT OFFICE.

THEODOR BERGMANN, OF GAGGENAU, GERMANY, ASSIGNOR TO JOHN H. VOLKMANN, OF NEW YORK, N. Y.

VENDING APPARATUS.

SPECIFICATION forming part of Letters Patent No. 447,862, dated March 10, 1891.

Application filed November 20, 1888. Renewed December 10, 1889. Serial No. 333,179. (No model.)

To all whom it may concern:

Be it known that I, THEODOR BERGMANN, a resident of Gaggenau, in Baden, Germany, have invented an Improved Vending Apparatus, of which the following is a specification.

The object of my invention is to provide improvements in coin-chutes for vending apparatuses; also, to provide improvements in coin conveyers and supports for such apparatuses, and improved means for closing the coin-chute to prevent the entry of coins after the packages have been removed from the apparatus.

15 The invention consists in the details of improvement and the combinations of parts that will be more fully hereinafter set forth, and pointed out in the claims.

Reference is to be had to the accompanying drawings, forming part of this specification, in which—

Figure 1 is an elevation of a vending apparatus, the back of the apparatus being removed, disclosing my improvements. Fig. 2 is a vertical cross-section on the line $k'k$, Fig. 1. Fig. 3 is an enlarged detail sectional view on the plane of the line $c'c'$, Fig. 6, showing the coin conveyers and supports and a portion of the coin-chute. Fig. 4 is a vertical cross-section on the line $c'c'$, Fig. 1. Fig. 5 is an enlarged detail plan view on the plane of the line $k'k'$, Fig. 3, showing my improved coin conveyer and support in the rearward or coin-receiving position; and Fig. 6 is a similar detail view showing the coin conveyer and support in the forward or coin-expelling position.

In the accompanying drawings, the letter A represents the casing of a vending apparatus, which may be of approved construction. 40 In the drawings, the casing A is provided, as shown in Fig. 1, with two compartments B, in which may be placed packages D, one upon the other, as shown.

Between the two compartments B, I prefer 45 to place two coin-chutes E, that extend from the front of the casing A about to its back, as clearly shown in Fig. 2. These coin-chutes E at the front of the casing come opposite openings a therein, through which the coins 50 may be passed to said chute. The chutes E are cut away for a portion of their length, as

at b, (see Fig. 1,) thereby leaving ledges b' at the sides, upon which the edges of a coin may rest. These ledges are at such a distance apart that a coin of proper size will rest 55 upon them and pass down the chute; but a coin of less diameter will fall through said chute to a receptacle F.

On the outside of the casing A, I prefer to 60 secure a slotted block d, whose slot is aligned with the opening a. The slot in the block d should be of such a size as to permit the entry of a coin of proper size, but to prevent the entry of a coin of larger size. The lower ends of the chutes E lead to the upper ends 65 of chutes G, so that coins may pass from a chute E to a chute G. (See Fig. 2.) The chutes G are situated back of the compartments B, their lower ends coming about in line with the bottom of the compartments B. 70 The chutes G consist of two plates e f, that are connected together at their edges for a short space near their lower ends by an intermediate strip or the like, but are not connected at their edges above that part whereby 75 a chute having an open upper and lower part is formed. The bottoms of the chutes G are also open for the exit of coins, one side of said chute at the lower end being preferably cut away, as at g², for the passage of a coin. 80

H is a lever that is pivoted at about its center, preferably about in line with the center of the chutes E when two such chutes are used. The outer ends of the lever H pass through the under openings in the length of 85 the chutes G and extend across said chutes, as shown in Fig. 1. The lever H is to be so balanced that when a coin of proper weight passes into the chute G it will depress said lever until its lower end comes against a stop 90 g in the chute. The lever thus depressed fills the under opening in the length of the chute, thereby forming a tread for the coin to run upon to find its exit at the lower end of said chute. The lever H should be so balanced that if a coin of less weight than the proper coin to be used is passed into said chute said lever will not be depressed, but the coin will run along the upper edge of said lever and pass out through the upper opening of the chute G, as shown in dotted lines 95 at the left in Fig. 1. The lever H may be 100

otherwise pivoted and balanced, if desired. If desired, the lever H may be replaced by a spring that will act in the same manner.

I are springs that pass along the outer side 5 of the chutes G. These springs extend slightly below the lower ends of the chutes G, and each carries a pin h, that passes through an opening i in the outer sides of the chutes G, so as to come in line with and stop the 10 passage of a coin through said chute for the purpose hereinafter set forth. The lower ends of the compartments B are cut away, thereby leaving ledges or guides l² at the sides, upon which the packages may rest and 15 along which they are pushed when being expelled from the apparatus.

Below the compartments B are my improved coin conveyers and supports J, that are adapted to receive coins from the chutes 20 G. The coin conveyer and support J is constructed as follows: j is a bar that is guided at one end in a plate l, the other end of which is connected to a sleeve m, which sleeve surrounds a rod n, that is suitably supported in 25 the casing. A spring o, that surrounds the sleeve m, presses at one end against a shoulder on said sleeve, and at the other end against a stop within the casing, and thereby tends to move the coin conveyer and support 30 backward under the coin-chute G. By means of a ring or other handle that projects through the casing from the sleeve m, the coin conveyer and support may be drawn forward. From one side of the bar j of the coin conveyer and support J project lugs p, that are 35 in the form of hooks that face each other, as shown in Figs. 5 and 6, thereby leaving a recess into which a coin may pass. In the outer ends of the lugs p are set-screws q, that 40 are adapted to project from said lugs into the recess formed by said lugs. In the bar j of the coin conveyer and support is placed a set-screw r, that is about in line with one of the set-screws q, and that is adapted to pass 45 through the bar j and into the recess formed by the lugs p. On the same side of the bar j with the set-screw r in lug s, carried by the bar j, is pivoted a lever L. One end of the lever L is pressed toward the bar j by a helical 50 spring t, that is preferably situated at the opposite end of said lever. u is a set-screw that is carried by the lever L, and that passes freely through the bar j of the coin conveyer and support J, as clearly shown in Figs. 5 and 55 6. This set-screw u is adapted to pass into the recess formed by the lugs p.

To support a coin of proper size in my improved coin conveyer and support, the set-screws q, q, r, and u are adjusted so that the 60 edges of a coin will rest upon and between the ends of said set-screws. This adjustment may be made very delicate, so that when the lever L is turned on its pivot to move the set-screw u away from contact with the coin M 65 said coin will lose its support and will drop from the coin-conveyer.

In order to move the lever L on its pivot at

the proper moment, I secure in the path of the coin conveyer and support J a rod N, that is preferably adapted to pass through one of the lugs p and through the bar j, and to come in contact with the lever L to move the end of the lever carrying the set-screw u slightly outward, as clearly shown in Fig. 6. This rod N is situated over a chute O, that is 70 adapted to receive the coins from the conveyer and support, when said coin has acted to push a package from the compartment B above said conveyer.

P is a lever that is pivoted below the coin 80 conveyer and support J, so that its upper end comes in line with the lower edge of a coin when carried by said conveyer, said lever being adapted to prevent the return of the conveyer after the conveyer has passed said lever and while the coin is retained in said conveyer. A more full description of this lever will be found in Letters Patent No. 413,009, Adriance, dated October 15, 1889.

R is a weight that I place in the compartment B upon the pile of packages D. To the weight R is attached a chain or other connection a², the upper end of which is connected to a rod b². This rod b² I prefer to make with the horizontal portion, to which 95 said chain is secured and with a vertical portion, the lower end of which is adapted to come in line with the opening a in the casing. By means of a spring d² the rod b² is elevated when the weight R does not draw upon the 100 connection a². When the weight R is placed upon the packages D, the spring d² will raise the rod b², moving it out of line with the opening a. When the last package has been removed from the compartment B, the weight R, 105 by drawing upon the connection a², will draw down the rod b², thereby moving its end over the opening a², by this means preventing the entry of any more coins until the weight R has been elevated by placing packages beneath it. By the above construction I produce an automatic closing of the coin-opening when the last package has been delivered.

My improvements operate as follows: Supposing the compartment B to be provided 115 with packages and the weight R placed upon said packages, the rod b² thereby being moved out of line with the opening a and the coin conveyer and support J to have been moved by the spring o back beneath the coin-chute 120 G in position to receive a coin. The coin is now placed in the apparatus when it passes along the chute E, thence to the chute G, and depresses the lever H, which forms a tread for the coin. The coin then passes from the 125 chute G into the coin conveyer and support J, and rests upon the ends of the set-screws q, q, r, and u. The purchaser now draws upon the sleeve m, which moves the coin-conveyer forward, thereby bringing the coin M in contact 130 with the lowest package D of the pile of packages, thereby pushing said package forward along its guides l², so that it will drop over the edge T, and through the opening at the end of

said guides, and fall down in front of the apparatus, as shown in Fig. 4. As the coin conveyer and support J is moved forward and reaches the rod N, said rod will pass through said conveyer, and at about the moment that the package has been pushed as far as the coin can push it the rod N will strike the lever L, thereby moving said lever, and with it the screw u, from contact with the coin, thus releasing the coin, when the coin will drop from the coin conveyer and support J into the chute O, the package meanwhile dropping from the coin conveyer and support J. The spring o will return the conveyer and support J to its position beneath the coin-chute for receiving another coin when the operator releases the ring or handle. When the conveyer and support is in the coin-receiving position, it will engage the end of the spring I and move said spring outward so as to draw the pin h outward to give a free passage through the chute G for a coin. When the coin conveyer and support is moved forward, the spring I will also move forward, so as to bring the pin h across the chute G. If now a person should place a coin into the apparatus when the coin conveyer and support is not beneath the chute G, the pin h will prevent the passage of the coin from the chute G. On the return of the conveyer, the lever l being moved outward, as before shown, thereby drawing the pin h outward, the coin that was retained in the chute G will be permitted to pass to the coin conveyer and support, so that the purchaser may get his package without losing his coin.

Although I have shown an apparatus containing two compartments for packages, two sets of coin-chutes, and two coin-conveyers, it is evident that the apparatus may be constructed with only one such set of devices or with any number desired. It is also evident that the relative arrangement of parts may be varied to suit the requirements of different apparatuses.

Having now described my invention, what I claim is—

1. The inclined chute G, open on its upper and lower sides, combined with the pivoted balanced lever H beneath said chute, the end of said lever passing into said chute from the under side, said lever forming the bottom of the chute and being adapted to be depressed by a coin of proper weight to form a tread for the coin, and to cause a coin of less weight to pass out of the upper side of the chute, substantially as described.

2. The inclined plates e f, connected together on their edges near one end and free

on their edges above said connected part, thereby forming open upper and lower sides, 60 combined with the balanced lever H below said plates, the end of said lever being passed between said plates from the underside, thereby forming a tread for a coin of proper weight, and causing a coin of less weight to pass 65 through the upper side of the chute, substantially as described.

3. The chute E, having an opening b and edges b' at the sides of said opening, combined with the inclined chute G, having open upper 70 and lower sides, and with the balanced lever H below said chute, the end of said lever being passed within said chute from below, and with a stop g for the end of the lever, said lever thereby forming a tread for a coin, substantially as described. 75

4. In a vending apparatus, the combination, with the casing having an opening a for the entry of coins, of a rod b² for passing across said opening, a spring for raising said 80 rod, and a weight for depressing said rod, substantially as described.

5. The combination, with a chute having an opening i, of a spring I, having a pin h for passing into said opening, and with a 85 pusher that engages said spring, and a lever H for passing across said chute, all arranged for operation substantially as herein shown and described.

6. In a vending apparatus, the bar j, carrying screws q q and r, combined with the movable screw u, said screws being adapted to support a coin in the conveyer and to release said coin when the screw u is moved, substantially as described. 90

7. In a vending apparatus, the bar j, carrying screws q and r, combined with the movable screw u and with the rod N for moving said screw, all arranged for operation substantially as herein shown and described. 100

8. In a vending apparatus, the bar j, carrying screws q and r, combined with the lever L and screw u, that is carried by said lever, and with the rod N for moving said lever L and screw u, substantially as described. 105

9. In a vending apparatus, the bar j, having lugs p p and screws q q r, combined with the lever L, having screw u and the spring t, and with the rod N for moving the lever L and screw u, all arranged for operation substantially as herein shown and described. 110

THEODOR BERGMANN.
